Geo. P. Kimmel.
ATTORNEY.

UNITED STATES PATENT OFFICE.

ORMOND C. MALCOLM, OF AUBURN, NEW YORK.

BRUSH-HOLDER.

1,394,205.

Specification of Letters Patent. Patented Oct. 18, 1921.

Application filed August 6, 1920. Serial No. 401,641.

To all whom it may concern:

Be it known that I, ORMOND C. MALCOLM, a citizen of the United States, residing at Auburn, in the county of Cayuga and State 5 of New York, have invented certain new and useful Improvements in a Brush-Holder, of which the following is a specification.

This invention relates to brush holders 10 and more particularly to paint brush holders for protecting such brushes when not in use.

The object of the invention is to provide a holder of this character which will completely incase the bristles of the brush and yet permit a preserving liquid to contact 15 with the bristles.

Another object is to provide a brush holder having means for supporting it out 20 of contact with the bottom of a bucket or other support and which may be suspended from the edge of the bucket top if desired.

With these and other objects in view, the invention consists in certain novel features 25 of construction as hereinafter shown and described and then specifically pointed out in the claims and in the drawings illustrative of the preferred embodiment of the invention.

30 In the accompanying drawing:

Figure 1 represents a side elevation of a brush holder constructed in accordance with this invention and shown in closed position:

Fig. 2 is an edge view thereof.

35 Fig. 3 is a similar view taken from the opposite edge.

Fig. 4 is a front elevation of the holder shown in open position with a brush mounted therein, and,

40 Fig. 5 is a longitudinal section thereof, taken on the line 5—5 of Fig. 1.

In the embodiment illustrated the brush holder constituting this invention is shown in the form of a protective casing 1 composed of two sections 2 and 3 preferably of uniform size and shape and hingedly connected at one edge by hinges 4, the free edges thereof being secured when the sections are closed by latches or clips 5.

50 These sections 2 and 3 as shown taper toward their upper ends to adapt them for use in connection with a paint brush shown at B but obviously they may be used in connection with other brushes and when so used 55 are shaped to conform to the shape thereof.

The sections 2 and 3 have inturned flanges 6 at their lower ends which meet when the sections are closed and protect the edge of the brush preventing said edge from becoming bent or injured. These sections 2 and 3 60 have inwardly offset bristle engaging members 7 at their lower ends which are here shown instruck with shoulders 7^a which engage the inner ends of the bristles adjacent the head of the brush (see Fig. 5) to prevent the weight of the brush resting on the bristles. These instruck portions are equipped with apertures 8, similar apertures being formed in the sections adjacent these portions 7 to permit the preserving fluid to 70 enter the casing and keep the bristles of the brush soft.

The bristle engaging elements 7, as is shown clearly in Fig. 5, clamp the bristles between them to prevent undue spreading 75 thereof.

The casing or holder 1 is provided at its lower end with longitudinally extending fingers 9 spaced laterally from each other and designed to form feet for supporting the 80 casing out of contact with the bottom of the paint pot or other support.

A hook 10 is carried by the upper end of one of the sections and is designed to be engaged with the edge of a bucket or paint 85 pot when it is desired to suspend a holder therefrom. Obviously this hook may be engaged with any other suitable support.

In the use of this holder the brush B after having been cleaned is placed therein in the 90 position shown in Fig. 4 and the sections are then closed and secured together by the fasteners 5. The holder will then be hung by the hook 10 on a suitable support or it may be placed in a container having a preserving 95 liquid therein such as oil which enters the casing 1 through the apertures 8 and retains the bristles of the brush in soft flexible condition.

The preferred embodiment of the invention is disclosed in the drawings and set forth in the specification, but it will be understood that any modifications within the scope of the claim may be made in the construction without departing from the principle of the invention or sacrificing any of its advantages.

What I claim is:

A brush holder comprising sections hingedly connected along one side edge and 110

having means for detachably connecting their free edges, said sections having in- struck portions arranged to clampingly en- gage the entire outer faces of the bristles of 5 the brush to be housed in the casing and re- tain them in proper shape, said portions having shoulders to engage the brush at the

junction of the bristles with the head to hold the brush against longitudinal move- ment in one direction and prevent the weight 10 of the brush from resting on the bristles.

In testimony whereof, I affix my signature hereto.

ORMOND C. MALCOLM.
